ROLLER SCREEN

Filed Aug. 6, 1927

HARRY W. VALENTINE.
INVENTOR.

BY Harry P. Schroeder
ATTORNEYS.

UNITED STATES PATENT OFFICE.

HARRY W. VALENTINE, OF OAKLAND, CALIFORNIA.

ROLLER SCREEN.

Application filed August 6, 1927. Serial No. 211,072.

This invention relates to the class of screens and pertains particularly to a spring controlled window screen.

The present invention has for one of its objects to provide, in a manner as herein-after set forth, a window screen which can be conveniently rolled into a protective casing at the top of a window until ready for further use.

10 Another object of the present invention is to provide a rolling window screen employing an improved means for securing the control spring to the screen carrying cylinder.

15 Still another object is to provide, in a manner as herein-after set forth, an improved means for mounting a control spring upon a screen cylinder supporting shaft.

Numerous other objects and advantages of 20 the present invention will become apparent as the description proceeds and the same will be best understood from a consideration of the following detailed description taken in connection with the accompanying drawings forming a part of this invention, with the understanding, however, that the invention is not confined to any strict conformity with the showing of the drawings but may be changed or modified so long as such 25 changes or modifications mark no material departure from the salient features of the invention as expressed in the appended claims.

In the drawings:

35 Fig. 1 is a longitudinal section through the roller screen structure.

Fig. 2 is a detailed sectional view through the screen roller cylinder.

40 Fig. 3 is a section taken on the line 3—3 of Fig. 2.

Referring now to the drawings in detail, an elongated casing 2 of substantially semi-cylindrical cross sectional design houses the roller structure. The ends of the casing are closed by the end caps 4 and 5 each of which is provided with the flange 4^a and 5^a for facilitating securing the device in position.

A screen roller cylinder 6 is positioned in the casing 2 and is mounted upon the shaft

50 7, one end of which is reduced and squared as at 8 and engages in a square hole 9 formed in the cap 4 and by reason of this is held against rotation. The opposite end of the shaft is engaged in the cap 5 as shown.

55 Upon the squared end 8 is mounted a lock-

ing disc 10 which disc is provided upon its periphery with a notch 10^a.

A portion of the shaft adjacent the squared end 8 is reduced as at 11, being slightly larger than the end 8, and upon the portion 11 a cone-like spool 12 is mounted, the larger end or base portion bearing against a cupped end piece 14, and the inner or smaller end bearing against the shoulder 13 formed at the inner end of the reduced portion 11. The base portion of the spool 12 has an annular lip 15 formed concentrically thereon which is swaged over after being extended through the member 14 to maintain the spool and this member in loose connection. The end piece 14, as shown closes one end of the cylinder 6, the flange of the piece being directed outwardly. The other end of the cylinder is closed by a similar member 14^a.

Surrounding the shaft 7 is a relatively long coil spring 16 of the type usually employed in shade rollers, one end of the spring extending over and engaging the tapered spool 12. This spool acts to prevent the spring when tightened, from binding upon the shaft, and the end of the spring upon the spool is engaged through the hole 17 in the adjacent end piece.

The cylinder 6 is rolled from a flat sheet 85 as will be readily understood and the longitudinal edges are secured together by forming a locked seam as indicated at 18 and each end edge of the cylinder is bent inwardly over the flange of the adjacent piece, 90 a notch 20 being cut into the edge of the end piece to receive the seam of the cylinder, thus locking the end pieces 14 and 14^a in the cylinder, as will be readily understood from a consideration of Figs. 4 and 5.

Upon the outer face of the end piece 14 is secured a pawl 22 which engages the notch 10^a of the disc 10, thus locking the cylinder against rotation after the spring 16 has been tightened. Manipulation of the pawl 22 for rolling or unrolling the cylinder is accomplished by the insertion of a suitable instrument through the aperture 23 in the end cap 4.

Having thus described my invention, what I claim is:

1. In a roller screen structure of the character described, a fixed shaft, a cylinder for carrying a screen fabric rotatably mounted upon said shaft, a spiral spring surrounding

said shaft, one end of said spring being fixed to the rotatable cylinder and the other end to the shaft, a tapered member mounted at one end of the shaft, said member being rotatable with respect to the shaft and to the spring, and means for preventing longitudinal movement of the tapered member along the shaft.

2. In a roller screen structure of the character described, a fixed shaft, a cylinder for carrying a screen fabric rotatably mounted upon said shaft, a spiral spring surrounding

said shaft, one end of said spring being fixed to an end of said rotatable cylinder and the other end being attached to the shaft, a tapered bearing mounted upon a reduced portion of the shaft between the shaft and the first mentioned end of said spring, said bearing thus being fixed against longitudinal displacement and being rotatable relative to the spring, and to the shaft.

In testimony whereof I affix my signature.

HARRY W. VALENTINE.
